UNITED STATES PATENT OFFICE

JOHN H. BOSS, OF BALTIMORE, MARYLAND, ASSIGNOR OF ONE-HALF TO JOSEPH STABELE, OF BALTIMORE, MARYLAND

WINDOW SHADE BRACKET

Application filed May 5, 1931. Serial No. 535,114.

This invention relates to a shade roller support or bracket and has special reference to a combined shade roller and curtain rod fixture.

5 One important object of the invention is to improve the general construction of devices of this character.

A second important object of the invention is to provide a novel form of such fixture wherein there is a bracket slidable along 10 the body or base of the fixture so as to accommodate variations in the length of the shade roller.

A third important object of the invention 15 is to provide a device of this character wherein the principal parts can be made economically from sheet metal.

With the above and other objects in view, as will be hereafter apparent, the invention 20 consists in general of certain novel details of construction and combinations of parts hereinafter fully described, illustrated in the accompanying drawings and specifically claimed.

25 In the accompanying drawings like characters of reference indicate like parts in the several views, and:

Figure 1 is a front elevation of the invention.

30 Figure 2 is a section on the line 2-2 of Figure 1.

Figure 3 is a section on the line 3-3 of Figure 1.

Figure 4 is a perspective view of the shade 35 roller bracket used herewith.

Figure 5 is a perspective view of a presser or locking plate used herewith.

Figure 6 is a perspective view of a locking cam used herewith.

40 In the embodiment of the invention shown in the drawings there is provided a rectangular base plate 10 having its edges bent back to form a peripheral flange 11. Adjacent each corner this plate is provided with a screw receiving opening 12 by which screws may be used to secure the device to a window frame. This base is preferably made of sheet metal and U-shaped slits 13 are formed adjacent the top and bottom edges of the base. The metal defined by

these slits is struck out forwardly of the remainder of the body to provide broad but low tongues 14 extending toward each other in parallel relation.

5 In connection with this base there is provided a bracket having a rectangular bracket base 15 arranged with its ends beneath the tongues 14. Projecting from one side of this plate and extending forwardly from between the tongues 14 is a flange 16 having a suitable slot or opening 17 to receive the pintle of a shade roller. Similarly a flange 18 extends forwardly from the other side edge of the base 15 and these two flanges are provided with aligned bearing openings 19.

A presser plate 20 rests at its ends on the outer or front faces of the tongues and is provided with a slot 21 through which the flange 18 projects. It will be noted from Figure 5 that the middle portion of the presser plate is offset from the ends and, as shown in Figure 1, the major portion of this plate lies between the flanges 16 and 18 of the bracket.

70 A cam member is provided to force the presser plate 20 toward the base 15 and thus to clamp the tongues 14 between these parts and thereby hold the bracket in adjusted position on the base 10. This cam member is in the form of a strip of metal 75 bent to form a substantially L-shaped lever having a short presser arm 22 and a long operating arm 23. At the junction of these arms the lever is provided with laterally extending journal lugs which engage in the bearing openings 19 and thus pivotally mount the cam member, being carried by said flanges.

80 When moved into the position shown in Figure 3 the cam member causes the bracket to be securely clamped against movement along the base 10 but, when the arm 23 is swung outwardly and upwardly from this position pressure on the plate 20 is released and the bracket is free to move and thus to be adjusted to suit the length of shade roller used. Both the base 15 and plate 20 have those parts engaging the tongues 14 slightly roughened or serrated to securely grip these tongues.

85 Preferably a split post 25 is mounted on

the base 10 so that the end of a tubular curtain rod may be fitted securely thereon and obviously it is intended that these fixtures be used in pairs as is common in all such fixtures.

It is obvious that minor changes may be made in the form and construction of the invention without departing from the material principles thereof. It is not therefore desired to confine the invention to the exact form herein shown and described, but it is desired to include all such as properly come within the scope claimed.

What is claimed as new, is;

1. A shade roller fixture including a base, a pair of opposed transversely extending tongues carried by said base and spaced forwardly therefrom, a bracket member having a base provided with ends extending behind said tongues and having side flanges projecting forwardly from between said tongues, one of said flanges having means to receive the pintle of a shade roller, said flanges having alined bearing openings, a presser plate between said flanges and having its end resting on said tongues, and a cam member provided with an operating arm pivotally mounted on said flanges and between the same, said cam member being arranged to force the presser plate toward the base of the bracket and thereby clamp said tongues.

2. A shade roller fixture including a base, a pair of opposed transversely extending tongues carried by said base and spaced forwardly therefrom, a bracket member having a base provided with ends extending behind said tongues and having side flanges projecting forwardly from between said tongues, one of said flanges having means to receive the pintle of a shade roller, said flanges having alined bearing openings, a presser plate between said flanges and having its end resting on said tongues, said presser plate extending at one side beyond the bracket and being slotted to receive the flange at said side, and a cam member provided with an operating arm pivotally mounted on said flanges and between the same, said cam member being arranged to force the presser plate toward the base of the bracket and thereby clamp said tongues.

In testimony whereof I affix my signature.
JOHN H. BOSS.
